FLUORESCENT SUBSTANCE

Hans Rabe, Ludwigshafen-on-the-Rhine, Germany, assignor to I. G. Farbenindustrie Aktiengesellschaft, Frankfurt-on-the-Main, Germany

No Drawing. Application November 28, 1933,
Serial No. 700,080. In Germany December 2,
1932

7 Claims. (Cl. 260—168)

The present invention relates to substances which are soluble in hydrocarbon oils and produce fluorescence therein, and to a process of making such substances.

5 It is already known that by the polymerization of aromatic hydrocarbons containing more than one nucleus substances are obtained under appropriate conditions of temperature and in the presence of catalysts of the Friedel Crafts' type which when dissolved in a mineral oil impart to the latter a green fluorescence.

These products have a from tarry to asphaltic consistency, may be dissolved in lubricating oils while warming and have the disadvantage that 15 the greater part of them is precipitated again after allowing the solution to stand for some time and that in many cases they give only a slight opalescence. These products furthermore are not soluble in benzines but are precipitated by 20 them.

It has been suggested elsewhere to produce substances producing fluorescence, which are readily soluble in hydrocarbon oils (by which expression I understand heavy oils or middle oils or 25 lubricating oils or liquid motor fuels, such as benzines, or other liquid hydrocarbon fractions—whether they may be of naphthenic or paraffinic base), even at low temperatures, by subjecting olefines of purely aliphatic constitution which are 30 liquid at ordinary temperature or halogenated paraffin wax hydrocarbons to condensation with polynuclear organic substances in which none of the nuclei is saturated with hydrogen, at an elevated temperature, in the presence of condensing 35 catalysts of the Friedel Crafts' type, in particular aluminium chloride. Those of the aforesaid polynuclear substances are of particular advantage which are devoid of substituents. As 40 such substances may be mentioned unsubstituted polynuclear aromatic hydrocarbons, such as naphthalene or anthracene or phenanthrene, or polynuclear heterocyclic compounds, such as carbazole. As olefines suitable as initial materials 45 for this conversion may be mentioned the liquid products obtained by the cracking, preferably in the vapor phase, of paraffinic hydrocarbons, such as hard or soft paraffin wax, petrolatum, or oils entirely or mainly consisting of paraffinic 50 hydrocarbons and also normally liquid olefines obtained by the dehydration of higher aliphatic alcohols, preferably such as contain at least 6 carbon atoms, such as octodecyl alcohol.

The said condensation of olefines and polynuclear aromatic substances, preferably hydrocarbons, is effected at temperatures between 70° and 250° C., preferably between 125° and 200° C. In order to carry off the great heat evolved by the said condensation, the treated materials are preferably diluted with an inert diluent as for 55 example a benzine fraction boiling between 150°

and 200° C., or another oil boiling at the same or higher temperatures, and externally cooled simultaneously. The amount of polynuclear aromatic substances should be greater than 20 per cent of the amount of olefine employed, but is 5 advantageously not greater than from 60 to 70 per cent of the said amount of olefines since a surplus does not take part in the reaction, but acts only as a diluent and would have to be distilled from the resulting condensation product. 10 The intensity of the fluorescence caused by a certain amount of the condensation product is greater, the greater the amount of aluminium chloride employed. Preferably from 20 to 50 per cent of aluminium chloride with reference to 15 the amount of the initial olefines to be condensed are employed, though larger amounts of aluminium chloride may be used. The products obtained according to the present invention ordinarily have a mean molecular weight of between 20 600 and 800.

The substances producing fluorescence thus obtained are thickly liquid, viscous products which at ordinary temperature may be dissolved 25 in hydrocarbon oils of naphthenic or paraffin base, such as in lubricating oils or in benzine. No precipitation or resinification occurs in the oils mixed with the said substances. The oils containing these substances are entirely clear in 30 transmitted light. An addition of from 0.1 to 0.2 per cent is sufficient for imparting to the oil a red color in transmitted light and a green color in incident light.

The said products, however, when added to hydrocarbon oils and especially lubricating oils, sometimes have the disadvantage that they produce a green fluorescence having a bluish shade which is undesirable and which fluorescence often has not sufficient stability to light. 40

I have now found that this objection is avoided by employing for the condensation not only condensing agents of the Friedel Crafts' type, in particular aluminium chloride, but also halides of metals of the 1st and 2nd groups of the periodic system, as for example NaCl, NaBr, KCl, CuCl₂, HgCl₂ and CaCl₂, which salts do not catalyze the Friedel Crafts' reaction, but which diminish the action of the condensing catalyst. The method of working is the same as when using the catalysts without the additions. The products obtained, when added to an oil for example in an amount of from 0.2 to 1.0 per cent, impart a fluorescence of the desired shade of color and of good stability to light and oxidation, in particular to the oxidizing influence effected by the air. 50

The following examples will further illustrate how the said invention may be carried out in practice, but the invention is not restricted to 55 these examples.

Example 1

1 kilogram of naphthalene is condensed with 4 kilograms of an olefine fraction, boiling between 50° and 250° C. under atmospheric pressure and obtained by splitting soft paraffin wax at a temperature of 520° C. in the presence of 1.6 kilograms of aluminium chloride and 0.2 kilogram of sodium chloride while stirring. After the reaction mixture has attained a temperature of 150° C., the whole is kept at this temperature for an hour. It is then allowed to cool and stirred with water, and the sludge is separated off. The reaction product is distilled in vacuo at 2 millimeters (mercury gauge) up to 150° C., about 0.2 kilogram of a low-boiling oil passing over. The residue of 4.6 kilograms is a paste soluble in oil and benzine. An addition of from 0.1 to 0.2 per cent thereof to a yellow colored oil imparts thereto a strong green fluorescence with red transparency, the setting point also being lowered by about from 5° to 8° C.

Example 2

25 2 kilograms of a chlorinated soft paraffin wax having a chlorine content of 18 per cent are dissolved in 1 kilogram of a middle oil having a boiling point of from 250° to 300° C., 0.5 kilogram of naphthalene and a mixture of 1 kilogram of aluminium chloride and 0.1 kilogram of sodium chloride then being added to the solution while stirring. The whole is worked as in Example 1. A paste is obtained in almost quantitative yield which when added to lubricating oils imparts thereto a green yellowish coloration in reflected light and a red coloration in transmitted light and improves the setting point by about from 5° to 8° C.

Example 3

40 A product having the same properties as those described in Examples 1 and 2 is obtained by condensing 4 kilograms of a cracking product boiling between 100° and 250° C. (at 700 millimeters) derived from crude paraffin wax, for half 45 an hour at 165° C. with 1 kilogram of naphthalene, 0.5 kilogram of anthracene, 0.5 kilogram of carbazole and a mixture of 1.2 kilograms of aluminium chloride, 0.05 kilogram of sodium chloride, 0.03 kilogram of potassium bromide and 0.04 kilogram of cuprous chloride, the reaction product being worked up as described in the said examples. The final product also improves the coloration and lowers the setting point of lubricating oils by from 5° to 8° C.

Example 4

1.2 kilograms of naphthalene are condensed at 100° C. while stirring with 4 kilograms of a mixture of olefines obtained by the dehydration of higher alcohols, the condensation being effected with 2.5 kilograms of aluminium chloride. The reaction product is stirred with water, separated from sludge by filtration, dried, subjected to an after treatment with a mixture of 0.1 kilogram of aluminium chloride and 0.05 kilogram of mercury chloride at 100° C. and again treated with water. After drying the reaction product is distilled in a vacuum of 1 millimeter (mercury gauge). The residue remaining above 200° C. constitutes a paste which when added to an oil in an amount of 0.5 per cent imparts thereto a yellow-green fluorescence with red transparency and also lowers the setting 75 point by about from 5° to 8° C.

What I claim is:—

1. The process of producing a substance giving rise to fluorescence when dissolved in a hydrocarbon oil which comprises condensing a substance selected from the group consisting of 5 liquid olefines of purely aliphatic nature and halogenated paraffin wax hydrocarbons with a polynuclear aromatic hydrocarbon in which none of the nuclei is saturated with hydrogen, by contacting said substances with a catalyst of 10 the Friedel Crafts' type at a temperature between about 70° and about 250° C. in the presence of a halide of a metal selected from the 1st and 2nd groups of the periodic system which halide does not catalyze the Friedel Crafts' re- 15 action.

2. An oil dyeing and improving agent produced according to the process defined in claim 1.

3. The process of producing a substance giving 20 rise to fluorescence when dissolved in a hydrocarbon oil which comprises condensing a substance selected from the group consisting of liquid olefines of purely aliphatic nature and halogenated paraffin wax hydrocarbons with 25 naphthalene by contacting said substances with a catalyst of the Friedel Crafts' type at a temperature between about 70° and about 250° C. in the presence of a halide of a metal selected from the 1st and 2nd groups of the periodic system 30 which halide does not catalyze the Friedel Crafts' reaction.

4. The process of producing a substance giving 35 rise to fluorescence when dissolved in a hydrocarbon oil which comprises condensing a substance selected from the group consisting of liquid olefines of purely aliphatic nature and halogenated paraffin wax hydrocarbons with a polynuclear aromatic hydrocarbon in which none of the nuclei is saturated with hydrogen, 40 by contacting said substances with aluminium chloride at a temperature between about 70° and about 250° C. in the presence of a halide of a metal selected from the 1st and 2nd groups of the periodic system which halide does not catalyze the Friedel Crafts' reaction.

5. The process of producing a substance giving 45 rise to fluorescence when dissolved in a hydrocarbon oil which comprises condensing a substance selected from the group consisting of liquid 50 olefines of purely aliphatic nature and halogenated paraffin wax hydrocarbons with a polynuclear aromatic hydrocarbon in which none of the nuclei is saturated with hydrogen, by contacting said substances with a catalyst of the 55 Friedel Crafts' type at a temperature between about 125° and about 200° C. in the presence of a halide of a metal selected from the 1st and 2nd groups of the periodic system which halide does not catalyze the Friedel Crafts' reaction.

6. Process of producing a substance giving rise to fluorescence when dissolved in hydrocarbon oil which comprises condensing a purely aliphatic olefinic fraction boiling between 50° and 250° C. with a polynuclear aromatic hydrocarbon in 65 which none of the nuclei is saturated with hydrogen by contacting said substances with aluminium chloride at a temperature between about 70° and 250° C. in the presence of sodium chloride.

7. The process according to the preceding claim in which the polynuclear aromatic hydrocarbon is naphthalene and the condensation temperature is about 150° C.
